UNITED STATES PATENT OFFICE

102,679

DESIGN FOR A CIGARETTE EXTINGUISHER

Charles L. Fay, San Francisco, Calif.

Application April 17, 1936, Serial No. 62,181

Term of patent 3½ years

To all whom it may concern:

Be it known that I, Charles L. Fay, a citizen of the United States, residing in the city and county of San Francisco and State of California, have invented a new, original, and ornamental Design for Cigarette-Extinguishers, of which the following is a specification, reference being had to the accompanying drawing, forming part thereof.

I claim:

The ornamental design for a cigarette-extinguisher, as shown.

CHARLES L. FAY.
